UNITED STATES PATENT OFFICE

ERICK J. AJAX, OF MINNEAPOLIS, MINNESOTA, ASSIGNOR TO DOMINION ELECTRICAL
MANUFACTURING COMPANY, OF MINNEAPOLIS, MINNESOTA, A CORPORATION OF
MINNESOTA

DESIGN FOR A REFLECTOR HEATER

Application filed March 27, 1931. Serial No. 39,267. Term of patent 7 years.

To all whom it may concern:

Be it known that I, ERICK J. AJAX, a citizen of the United States, residing at Minneapolis, in the county of Hennepin and State of Minnesota, have invented a new, original, and ornamental Design for a Reflector Heater, of which the following is a specification, reference being had to the accompanying drawings, forming part thereof, wherein:

Fig. 1 is a perspective view of a reflector heater embodying my ornamental design, and

Fig. 2 is a front elevation of the same.

What is claimed is:—

The ornamental design for a reflector heater, substantially as shown.

ERICK J. AJAX.
